UNITED STATES PATENT OFFICE.

CARL J. HAZELTON, OF WORCESTER, MASSACHUSETTS, ASSIGNOR TO AMERICAN NARROW FABRIC COMPANY, OF WORCESTER, MASSACHUSETTS, A CORPORATION OF MASSACHUSETTS.

HOSE SUPPORTER.

Application filed February 24, 1922. Serial No. 538,936.

To all whom it may concern:

Be it known that I, CARL J. HAZELTON, a citizen of the United States, residing at Worcester, in the county of Worcester and 5 State of Massachusetts, have invented a new and useful Hose Supporter, of which the following is a specification.

This is in part a continuation of my allowed application Serial No. 455,764, filed 10 March 26, 1921, and also a continuation of my application, Serial No. 511,885, filed October 31, 1921.

This invention relates to a hose supporter of the type in which a metallic loop is employed to grip the fabric between its two arms and a button carried by a tab usually depending from the upper part of the loop. As heretofore put on the market these clasps have had a serious fault due to the fact that 15 when the stocking is gripped and put under strain, that strain comes along a central vertical line and therefore is sustained primarily by only a very small number of vertical threads. The result, very frequently, is the 20 production of so-called "runs" disfiguring and weakening the hose. Another defect of the usual clasps on the market is that the rubber collet is put on a headed stud in such a manner that the head alone is depended 25 upon to hold the collet in place. The result is that any unusual strain transverse to the plane of the clasp is likely to dislodge the collet from its supporting element and ruin the whole device.

30 This invention is designed to overcome these defects without revolutionizing the appearance of the article. More specifically stated, the objects of this invention are to provide a rubber covered button of such a 35 nature that the clamping grip between the button and the loop member takes place on an extended line transversely of a plurality of the wales of the hose fabric so that the strain on the fabric is equally distributed 40 throughout a wide area; so that a substantial number of threads, wales or stitches are simultaneously gripped and the danger of injury to the hose fabric or the appearance of runs in the hose will be avoided or very 45 much reduced; to provide a construction in which the rubber covering of the button is held firmly in position by a solid body of rubber having two adjacent heads of metal over an area at the front, so that even if

the rubber becomes weak through use or age 55 it cannot be pulled off its supporting elements; to provide a yielding transverse wall of rubber at the lower front corner of the button for the stocking to engage and on which the stocking has its bearing, whereby 60 the yield of this wall will reduce the strain on the stocking at this point and assist in preventing runs; to provide these features in such form that it will be equally effective, 65 in cooperation with the loop, to hold the fabric no matter at what angle the loop is applied; and to provide effective and inexpensive means for preventing the button from turning on its support so that the above mentioned objects will be maintained 70 after wear.

The invention also involves other features of construction which tend to assist in accomplishing the above mentioned objects as will appear.

75 Reference is to be had to the accompanying drawings, in which

Fig. 1 is a front elevation of a stocking supporter clasp constructed in accordance with this invention and showing it as it holds 80 the stocking in position under strain;

Fig. 2 is a similar view showing the parts with the stocking fabric removed and a part of the loop broken away;

Fig. 3 is a side elevation with the parts in 85 the same position;

Fig. 4 is a central vertical sectional view taken along the line 4—4 of Fig. 1;

Fig. 5 is a sectional view of the button and its supporting base plate on the line 90 5—5 of Fig. 3;

Fig. 6 is a horizontal central sectional view of the same;

Fig. 7 is a front elevation of a modified 95 form of button and base plate;

Fig. 8 is a central sectional view of the same, and

Fig. 9 is a similar view of another modification.

The hose supporter in the main figures of 100 the drawing is illustrated as in use and in a vertical position. The terms "top," "bottom," "front," etc. are, therefore, employed but these and similar terms being used for description are to be taken as relative and 105 not as restrictive.

The hose supporter clamp comprises two members, first the loop member and second

the button member, and these cooperate to grip or clamp the hose fabric when in place.

The invention is shown as applied to a construction involving an upper supporting loop 10 of well-known construction for receiving the elastic strap of the supporter. It is pivotally connected with a lower metallic loop 11. This loop 11 is provided with almost parallel but slightly converging side arms 12. These are connected across the end of the loop by a straight bar 14. These parts, of course, are all formed of a single piece of wire or metal stamping and preferably are integral with each other. They 15 form a button receiving loop at the bottom of the main loop 11.

Also supported by the loop 10 and hanging down behind the loop 11 is a piece 15 of textile material, usually in the form of non-elastic tape. This is provided on the bottom with a metal base plate 16 supported in vertical position in the usual or any desired way. This plate has the usual transverse perforations for receiving the tape 15.

20 Between the projections but spaced from them there are two rivets 18 located at a distance apart but at the same elevation. These are provided with heads 19 arranged symmetrically with respect to their shanks. 25 These heads are of such diameter that they are spaced only a short distance apart.

A rubber covering or collet 20 is applied to the shanks. The collet is of a peculiar and novel shape. It comprises a shank portion and a head portion. The shank is preferably of segmental cross section comprising the larger part of the circle and arranged with the flat area at the bottom as shown in Fig. 5. The front surface of the head 30 is of generally convex form and is provided with a depression or groove 21 extending parallel with the bottom of the head. The bottom of this groove serves as a seat for the heads of the rivets 19 which are thus 35 sunk well below the front of the head. This recess also causes the head to present two comparatively thin walls 22, the lower or bottom one of which in particular is, therefore, readily yieldable in an upward direction because instead of a solid rubber backing 40 behind it, there is only the groove 21.

When, therefore, the clamping members are brought into cooperative relation with the hose fabric clamped therebetween as 45 shown in Figs. 1 and 4 and a longitudinal strain is placed upon the hose, the transverse bar 14 of the loop member firmly clamps the hose fabric against the bottom surface of the collet with the clamp or grip thus extended over a plurality of the wales or lines of stitches of the fabric. Thus the strain on the fabric is widely distributed and there is little danger of the stitches being broken and runs caused as would be the case if 50 the fabric were simply gripped at one or two

lines or points. The strain on the fabric is also materially relieved or taken up by the yielding of the bottom wall 22 as indicated in Fig. 4. The fabric of the stocking is necessarily somewhat distorted by passing over the head of the button and back through the loop but this necessary distortion is minimized by the general convex and curved shape of the head which allows the section of the fabric passing over the button 75 and through the loop to be positioned in a smooth even form.

The segmental shape of the shank of the collet also insures when the loop member is placed in cooperative clamping position that 80 the loop member shall automatically assume its proper cooperative relation to the collet because even if the loop member is placed in position at an improper angle it will rock or swing into proper position.

85 The other forms of construction shown embody the more important features of the invention, particularly the wide transverse extended gripping surfaces of the loop and button members and the lower front yieldable wall of the button member, together with variations in the means for securing the collet to the base of the button member.

In the form shown in Figs. 7 and 8 I have introduced a modification which consists in making these two rivets integral with each other by connecting the shanks 30 across the top at 31. In both cases a block of rubber 25 is held under the heads of the rivets, or under this cross bar 31, to 100 prevent the withdrawal of the collet from its supporting parts. This piece of rubber 25 of course is integral with the walls of the collet and therefore constitutes a positive means for holding the parts in place.

105 In the form shown in Fig. 9 two studs 38 are shown with their heads resting on a metal plate 39, which holds the rubber and positively spaces the studs.

110 Although I have illustrated and described only two forms of the invention I am aware of the fact that other modifications can be made therein by any person skilled in the art without departing from the scope of the invention as expressed in the claims. Therefore, I do not wish to be limited to all the details of construction herein shown and described but what I do claim is:—

115 1. As an article of manufacture, a stocking support clasp comprising a rubber button with a straight bottom wall and a loop for gripping the fabric thereto having a straight transverse bar at the bottom for gripping the fabric against said straight wall in a transverse plane, said button having a groove on its front surface parallel with said bar and having a lower thin readily yieldable wall of rubber projecting beyond said groove, the lower surface of which is substantially continuous with said 120 125 130

straight bottom wall whereby under excessive strain on the fabric said wall will yield toward the center of the button.

2. As an article of manufacture, a stocking supporter clasp comprising a rubber button having a straight bottom surface and a loop for gripping the fabric thereto having side members engaging the sides of said button and a straight transverse bar 10 at the bottom gripping the fabric against said bottom surface, said button having a groove parallel with said bar on its front surface and having a lower wall of rubber integral with the button extending all 15 the way to the base of the button, constituting the lower boundary of said groove and of thin cross-section and located parallel with the holding bar so as to be capable of yielding toward the groove under excessive 20 strain on the fabric, the top of said wall being substantially parallel with the plane of the loop.

3. As an article of manufacture, a stocking supporter clasp comprising a support 25 having a rubber covering with a straight front or bottom surface in a transverse plane, the shank thereof being of circular form back of said straight bottom surface and a loop for gripping the fabric thereto 30 having side members engaging the sides of said support or covering, and a straight transverse bar at the bottom for gripping the fabric against said straight surface and keeping it in a flat condition all the way 35 across.

4. As an article of manufacture, a hose 40 supporter comprising a rubber button having a shank of segmental form constituting more than half of a circle and having a flat side and a metal loop having a rectangular end, one side in position for engaging the flat side of said shank and the two adjacent parallel sides spaced far enough apart to grip the opposite surfaces of the convex 45 part of the shank even when turned at an angle to the normal position.

5. As an article of manufacture, a stock-

ing supporter button having a straight bottom surface, said button having a groove on its front surface parallel with 50 said surface and having a lower thin readily yieldable wall of rubber projecting beyond said groove, whereby under excessive strain on the fabric said wall will yield toward the groove. 55

6. As an article of manufacture, a stocking supporter button having a straight bottom wall, said button having a groove parallel with said wall on its front surface and having a straight lower wall of 60 rubber integral with the button extending in a plane all the way to the base of the button, constituting the lower boundary of said groove and of thin cross-section and located so as to be capable of yielding in 65 a direction transverse to said straight bottom wall under excessive strain on the fabric, the top of said wall being substantially straight and parallel with the plane of the loop. 70

7. As an article of manufacture, a stud for a hose supporter having a shank and a head, both of segmental form constituting more than half of a circle, the flat surfaces of the head and shank being located 75 in the same plane at the bottom and extending longitudinally of the stud.

8. As an article of manufacture, a stud for a hose supporter having a shank and a head, both of segmental form constituting 80 more than half of a circle and having a vertical depth materially less than the horizontal length.

9. As an article of manufacture, a stocking supporter button having a shank and 85 head, said head having a groove on its front surface and having a lower thin readily yieldable wall of rubber projecting beyond said groove, along the lower side thereof, whereby under excessive strain on the fabric 90 said wall will yield toward the groove.

In testimony whereof I have hereunto affixed my signature.

CARL J. HAZELTON.
